ATTORNEY

UNITED STATES PATENT OFFICE.

ALFRED A. FAXON, OF PHILADELPHIA, PENNSYLVANIA.

DESIGN FOR A BINDER FOR PAPER BOXES.

SPECIFICATION forming part of Design No. 27,646, dated September 14, 1897.

Application filed March 15, 1897. Serial No. 627,705. Term of patent 3½ years.

To all whom it may concern:

Be it known that I, ALFRED A. FAXON, a citizen of the United States, residing in the city and county of Philadelphia, State of Pennsylvania, have invented and produced a new and original Design for the Binder of a Paper Box, of which the following is a specification, reference being had to the accompanying drawing, forming part thereof.

5 The leading feature of my design for the binder of a paper box is, first, a continuous band of quadrilateral form, and, next, tongues projecting upwardly and downwardly from the ends of said band.

10 The figure represents a perspective view of

15

a binder for a paper box embodying my design.

In the drawing, A designates a binder, the same consisting of the continuous band B of quadrilateral form and the tongues C, the latter projecting from the upper and lower edges of the ends of said band in respectively upwardly and downwardly directions.

What I claim is—

The design for the binder of a paper box, 25 substantially as described and shown.

ALFRED A. FAXON.
